CHARLES RADIGUER, OF ST.-DENIS, FRANCE, ASSIGNOR TO THE SOCIETE ANONYME DES ETABLISSEMENTS DELAUNAY-BELLEVILLE, OF ST.-DENIS, FRANCE, A CORPORATION OF FRANCE.

COMBINED LUBRICATING AND COOLING SYSTEM FOR INTERNAL-COMBUSTION ENGINES.

1,173,537.

Specification of Letters Patent. Patented Feb. 29, 1916.

Application filed May 4, 1915. Serial No. 25,863.

To all whom it may concern:

Be it known that I, CHARLES RADIGUER, citizen of the French Republic, residing at St.-Denis, Department of the Seine, in France, have invented certain new and useful Improvements in Combined Lubricating and Cooling Systems for Internal-Combustion Engines; and I do hereby declare the following to be a full, clear, and exact description of the invention, such as will enable others skilled in the art to which it appertains to make and use the same.

The method of lubricating engines is known in which the elements to be lubricated are placed in a casing so arranged as to collect the oil dripping off the lubricated surfaces, and in which the oil is drawn up by a special pump which supplies the same under pressure, to the surface in frictional contact. It is known that this method permits of increasing the unitary pressures on the rubbing surfaces and the relative speeds of these surfaces; it therefore permits of raising the forces by unit of weight, to a value which could not be reached with any other method of lubricating. The advantages derived from a circulation of water in the interior of pistons of internal combustion engines, is also known; this circulation of water permits of increasing the average pressure exerted by the gases on the pistons and therefore of increasing the speed of the said pistons, in particular when they have a large diameter. The circulation of water in pistons therefore permits, like lubrication in a casing, of increasing the power by unit of weight of the engine. The above will show the value of combining these two methods; lubrication in a casing and cooling of pistons by a circulation of water. This combination, however, presents a capital difficulty; water can only be supplied to the pistons through the medium of such elements as telescopic tubes or jointed knee joints, comprising stuffing boxes the absolute fluid-tightness of which cannot be insured; water leaking through these stuffing boxes drops into the casing and mixes with the oil contained therein, thereby depriving the latter of its lubricating properties.

It has been attempted to remedy this de-

fect by cooling the pistons not with water but with the oil contained in the casing; this system, however, has still some disadvantages, namely the co-efficient of transmission of heat by oil is less than that of water and therefore an adequate cooling is not always obtained; further, the casing oil must in turn, be cooled by a refrigerator having a circulation of water, the dimensions of which are prohibitive when it is desired to obtain powerful engines having a light weight and taking up little space.

The invention relates to a system permitting of combining lubrication in a casing and circulation of water in the pistons, while preventing any possibility of the introduction of water into the oil. The combination which leads to this result, is illustrated in the accompanying drawing, in which:—

Figure 1 is a longitudinal section through a vertical engine, taken on line X X of Fig. 2. Fig. 2 is a transverse section through the engine, taken on line Y Y of Fig. 1. Fig. 3 is a section through the brasses of the small end of the connecting rod, taken on line Z Z of Fig. 2.

The casing is divided into two compartments by means of a horizontal partition 1; the lubricating oil accumulates in the lower compartment and leakage water accumulates in the upper compartment. The horizontal partition 1 is above the space wherein the crank shaft operates; it is formed with openings 2 for the passage 2' of the connecting rods; each opening is edged with a screen 3 shaped somewhat after the manner of a chimney, within which the connecting rod operates. Oil may drip off:—

1, the bearings for the crankshaft and off the latter itself; 2, the brasses of the large end of the connecting rod; 3, the brasses of the small end of the connecting rod; 4, the cylinder and piston surfaces in frictional contact. It is evident that the oil coming from the shaft and its bearings cannot be projected into the upper compartment of the casing. The oil coming from the brasses of the head of the connecting rod also cannot be projected externally if the openings are sufficiently narrow and chimney-like screens are suitably arranged. The drops

of oil expelled by centrifugal force are projected tangentially to the circles described by the various points of the brasses or of the crank; an examination of the figures 5 show that these drops can strike the horizontal partition of the chimney-like screen, but they cannot penetrate the upper compartment of the casing.

The oil coming from the brasses of the 10 small end of the connecting rod may also be brought into the lower compartment of the casing. To this end, two wide slots 4, 4, (Fig. 2) are formed in each brass, in proximity to either end; the pipes 5, 5 secured 15 to the connecting rods open into these slots and terminate in proximity to the large ends or heads of the connecting rods. Lubricating oil is supplied in the usual manner, through the conduits 6, 6, into the region 20 between the brasses of the small end of the connecting rod; this oil spreads on the surfaces thereof and fills the circular channels 4, 4; the major portion of the oil escapes through the pipes 5, 5 which returns the 25 same to the lower compartment of the casing. A very small quantity of oil passes through the play left between the lining and the end of the bearing; this small quantity of oil may be lost without any great inconvenience but should it be desired to avoid 30 losses of any kind, the play or clearance left between the said lining and the end of the bearing, by means of a felt washer 7, 7 or other similar matter, secured to the brass 35 and in frictional contact with the lining. Finally, lubricating oil for the cylinders may freely drop into the upper compartment of the casing; this does not constitute a disadvantage as on the contrary having 40 been carbonized to a greater or lesser extent, has lost its lubricating properties and when mixed with the proper oil contained in the bottom of the casing, it gradually modifies the quality thereof. There is therefore no 45 reason to prevent said oil from reaching the upper part of the casing.

Moreover, the conduits for supplying water to the pistons and those for the outlet of same, must be arranged in such a manner 50 that all leakage water remains in the upper compartment of the casing and accumulates on the horizontal partitions whence it may be readily expelled to the exterior through the pipe 8. In order to obtain this result 55 it is sufficient that the different stuffing boxes of the telescopic tubes and the knee joints 9, 10 should move in vertical planes externally of the surroundings of the connecting rods; projected drops of water remain in these 60 vertical planes and cannot penetrate the lower compartment of the casing. This result is readily obtained if the water conduits are secured to the pistons in proximity to the diametral plane parallel to the engine 65 shaft, for instance, at 11, 11. The conduits

thus constituted are away from the connecting rods and externally of the surroundings of the same.

What I claim and desire to secure by Letters Patent of the United States is:—

1. The combination with an internal combustion engine having a cooling system for cooling the piston, and a lubricating system in which some of the lubricant is retained in the crank case, of a horizontal partition 75 above the bottom of the crank case to prevent the leakage from the cooling system and the lubricant in the crank case from mixing.

2. The combination with an internal combustion engine having a cooling system for cooling the piston, and a lubricating system in which some of the lubricant is retained in the crank case, of a horizontal partition 80 above the bottom of the crank case, said partition having an upwardly directed sleeve-like portion surrounding the connecting rod to prevent the leakage from said cooling system and the lubricant in the crank case from mixing.

3. The combination with an internal combustion engine having a cooling system for cooling the piston, and a lubricating system in which some of the lubricant is retained in the crank case, of a horizontal partition 95 above the bottom of the crank case, to prevent the leakage from the cooling system and the lubricant in the crank case from mixing, said partition having an upwardly directed sleeve-like portion tapering toward 100 the piston and so disposed that the leakage from said cooling system will fall upon the upper surface of said sleeve-like portion and so disposed that the lubricant below said partition will be thrown against the under 105 surface of said sleeve-like portion and thereby prevented from mixing with said leakage from the cooling system.

4. The combination with an internal combustion engine having a cooling system for 110 cooling the piston, and a lubricating system in which a portion of the lubricant is retained in the crank case, of means for collecting the leakage from the cooling system and also the lubricant from the cylinder, said means being adapted to prevent such collected leakage and lubricant from mixing with the lubricant in the crank case.

5. The combination with an internal combustion engine, of a horizontal partition disposed above the crank shaft and capable of collecting the used lubricant from the cylinder, means to conduct lubricant to the wrist pin of the piston, and means to return the lubricant conducted to the wrist pin to the lower portion of the crank case beneath said partition.

6. The combination with an internal combustion engine having a cooling system for cooling the piston, and a lubricating system 130

in which some of the lubricant is retained
in the crank case, of a horizontal partition
adapted to collect the leakage from said
cooling system and carbonized oil from the
cylinder and to prevent said leakage and
carbonized oil from mixing with the lubri-
cant in the crank case, and means for con-
ducting reusable lubricant from the wrist

pin of the piston to the crank case below
said partition. 10

In testimony whereof I affix my signature,
in presence of two witnesses.

C. RADIGUER.
